United States Patent Office.

JAMES LYON, OF NORFOLK, VIRGINIA.

Letters Patent No. 89,263, dated April 20, 1869.

IMPROVED MACHINE FOR CLEANING BRICKS.

The Schedule referred to in these Letters Patent and making part of the same.

To all whom it may concern:

Be it known that I, JAMES LYON, of Norfolk, in the county of Norfolk, and in the State of Virginia, have invented a new and useful Machine for Cleaning Bricks; and I do hereby declare that the following is a full, clear, and exact description thereof, reference being had to the accompanying drawings, and to the letters of reference marked thereon.

The nature of my invention consists in providing a machine for removing the adhering mortar from old bricks, by forcing them vertically through a series of rollers with corrugations.

To enable others skilled in the art to make and use my invention, I will proceed to describe its construction and operation.

On a suitable frame is mounted a series of sets of four rollers—one set vertically above the other—with corrugations, and of the proper size.

Each set of rollers is arranged in such a manner as to leave a space between them, on the inner side, equal to the size of the brick to be forced vertically between them.

The journals of these rollers, by means of movable boxes, are adjustable horizontally to or from each other.

Immediately over the opening, between the upper set of rollers, is a stationary box, or hopper, open at the bottom, and a little larger in width and depth than an ordinary building-brick, and of suitable height.

The front side of this box forms a door hinged at the bottom and falling outward on two supports to a nearly horizontal position, on which to place the rough brick to be fed into the machine.

Across this door, on the outside, and a short distance above the hinge, to give a short leverage, is mounted a pin, the ends of which play loosely in the slots of two arms, which open and close the door alternately.

By the upward stroke of a plunger, the door of the hopper is raised, which slides a brick into the machine, by means of the slotted arms, which are drawn up by a cross-head fastened to the plunger.

By the down-stroke of the plunger, the brick is forced between and turns the rollers, whose cutting-corrugations will remove the mortar from it as it passes between them.

At the same time the door of the hopper is opened by the slotted arms, to receive another brick.

The advantage of turning the rollers by the bricks, as they pass between them, over the mode of drawing the latter between the former by turning these by machinery, is that the cutting-corrugations of the roll-

ers do not become dulled so quickly by this method as by the other.

The bricks, if of different sizes, may be cut to the same size, and, if desired, the corrugated rollers may be so adjusted that they will cut corrugations in the bricks, which will be of advantage in laying them in the wall.

In the drawings—

Figure 1 represents a front view, with the plunger up and the door of the hopper closed by the slotted arms.

Figure 2 represents a vertical section through the middle of the machine, with the plunger down and pressing a brick between the rollers, with another brick on the door, which has been opened by the slotted arms.

Like letters denote like parts.

C C C represent the frame.

A A A A, the rollers, with diamond-pointed corrugations.

B B B B, the movable boxes, sliding and adjustable on the platforms E E, and in which revolve the journals b b.

D, the box, or hopper for receiving the rough brick, with the hinged door F, on which is mounted the pin G.

J, the plunger, for forcing the brick H between the corrugated rollers.

This plunger is over the centre of the opening, between the rollers, and receives a vertical motion by a piston or crank.

Fastened to the plunger is a cross-head, which gives motion to the slotted arms K K, to open and close the door of the hopper D.

The motion of the plunger is adjusted so that the lowest point it reaches, is a little over the middle of the upper set of rollers, so that the next brick which is fed into the machine will stand on the one already between the rollers.

Its operation is as follows:

The rollers are adjusted to suit the size of the brick.

The plunger, being at the lowest point, has opened the door of the hopper, by means of the slotted arms, attached to a cross-head of the plunger, and a brick has been placed on it.

By the upward stroke of the plunger, the door is closed, and the brick fed into the machine, where it is held standing uprightly on the rollers by the hopper.

In the down-stroke, the plunger presses on the brick, forces it between, and turns, by it, the rollers, whose cutting-corrugations will remove the mortar from it.

At the same time, the door of the hopper is again opened, another brick fed into the machine and forced between the rollers, pressing on and forcing the first one through the entire series, when it drops, with the removed mortar to the ground.

I claim, as my invention—

1. The door F, hinged as described, in combination with the pin, slotted arms, and cross-head of the plunger, substantially as described.

2. The sets of corrugated rollers A A A A, ar-

ranged as herein shown and described, and operated by means of forcing the bricks between them, as herein set forth.

The above specification signed by me, this 10th day of March, 1869.

JAMES LYON.
